GUN-PERFORATOR

Lloyd Spencer, Los Angeles, Calif., assignor of
one-third to Thomas C. Bannon, Altadena, and
one-third to John D. Chestnut, Newport Beach,
Calif.

Application July 1, 1946, Serial No. 680,649

7 Claims. (Cl. 164—0.5)

1

My invention relates to gun perforators, that is to tools which are adapted to be lowered into a well bore for the purpose of firing bullets through the surrounding casing and admit oil or gas from the formation traversed by the well bore.

Included in the objects of my invention are:

First, to provide a gun perforator which incorporates a novel arrangement wherein time delay primer charges are electrically ignited, such charges having sufficient time delay before generating substantial pressures that all charges become fully ignited before the ignition circuit is adversely affected.

Second, to provide a multiple unit gun perforator wherein the several propellant charges may be, if desired, set off by shock or detonation rather than mere ignition to accelerate the rise of propellant pressure, and thereby increase the acceleration of the bullet or penetrating charge.

Third, to provide a multiple unit gun perforator which incorporates a novel electric ignition means which is designed so that it may be readily and quickly replaced after each use of the gun.

Fourth, to provide a gun perforator which is sectional; that is, the gun perforator may comprise a plurality of multiple unit gun sections which may be connected end to end so that a large number of shots may be fired.

Fifth, to provide a novel electrical and mechanical coupling for gun perforators designed to permit submergence of the gun perforator to great depths in well liquids.

With the above and other objects in view as may appear hereinafter, reference is directed to the accompanying drawings, in which:

Figure 1 is a fragmentary elevational view of my gun perforator.

Figure 2 is an enlarged transverse sectional view through 2—2 of Figure 1.

Figure 3 is a fragmentary sectional view taken through a coupling joining adjacent gun perforator sections the section being taken substantially along the plane defined by the line 3—3 of Figure 2, portions of the electrical insulation being shown in elevation.

Figure 4 is an enlarged fragmentary sectional view through 4—4 of Figure 2 illustrating particularly the primer cartridge and the electric ignition means.

My gun perforator includes a series of gun perforator sections or bodies 1 threaded at their extremities and joined by couplings 2. The upper coupling is connected to a cable head 3 suspended from the end of a conductor cable 4.

2

Each body 1 is provided with a series of laterally directed internally threaded sockets 5 preferably divided into sets facing four directions. A propellant cartridge chamber 6 is provided at the inner end of each socket, forming with the socket a shoulder 7.

A gun barrel 8 is provided for each socket. A sealing disk 9 is interposed between the breech end of each gun barrel and shoulder 7. The disk 9 may be formed of soft metal, or formed of high strength material coated with soft material such as copper or lead in order that a fluid and pressure tight seal be obtained.

The gun barrel 8 is provided with a gun bore 10, the breech end of which is beveled slightly. A bullet 11 fits each gun bore, the base end of the bullet is reduced slightly in diameter and is provided with a retainer ring 12 of soft metal such as brass or copper preferably shrunk or pressed in place and shaped to fit the beveled breech of the gun bore. The disk 9 is provided with a central hole of such diameter that its margins engage retainer ring 12 to prevent backward movement of the bullet into the propellant cartridge chamber 6. The forward end of the bullet is covered by a seal plug 13, preferably of rubber, or synthetic rubber to exclude well fluids.

The chamber 6 receives a propellant cartridge 14 comprising a high explosive such as a double base propellant preferably in flake form packed in a suitable shell or container.

Each cartridge chamber 6 is intersected by a lateral bore 15 which is preferably tapered as it approaches the cartridge chamber. The bores 15 from each set of cartridge chambers are in vertical alignment and communicate with a vertical channel 16. Thus in the arrangement shown having four sets of gun units, four such channels are provided. The channels 16 receive an insulated conductor 17, having rudimentary insulated side plugs which form contact plugs 18 fitting each of the bores 15. The conductors are preferably pre-molded to fit the channels 16 and bores 15 as well as ends of the gun sections to be described hereinafter.

Each bore 15 receives a primer cartridge 19 tapered to fit the tapered portion of the bore. Each primer cartridge includes a shell 20, rounded at one extremity and adapted to be closed at the other extremity by an insulated disk 21 which carries a contact 22 electrically engageable with the wire in the contact plug 18. The disk 21 supports on its side within the primer cartridge an ignition filament 23. The filament may be covered with an exothermic, but non-explosive

mixture 24 such as matchhead compound, that is, a mixture containing both a fuel and an oxidizing agent.

The rounded apex or extremity of the primer cartridge 18 contains a small quantity of high explosive 25, for example balistite may be used. Between the mixture 24 and explosive 25 is an exothermic fuze mixture involving a fuel and an oxidizing agent 26 to delay ignition of the explosive. One of several material suitable for this purpose is a mixture of potassium perchlorate and asphalt. If this material is used it may coat the filament in place of the matchhead compound 24. Operation of the primer cartridge 19 will be described hereinafter.

The conductors 17 are held in place by bars 27 which fill the channels 16. The bars are secured by large-head set screws 28 which screw into the gun body at an angle relative to the bars so that their heads overlap the bars as shown best in Figure 2. The bars may be further retained by longitudinally extending key rods 29 fitting in mating grooves provided in the sides of the bars 29 and their channels 16. The conductors are compressed lightly by the bars to seal the ignition bores against entrance of well fluid.

The extremities of each gun perforator section or body 1 are reduced in diameter and externally threaded to fit the couplings 2. The reduction in diameter is sufficient to expose the axial ends of the bars 27 and key rods 29. Within the reduced threaded ends of the gun bodies are passages 30 which communicate between the channels 16 and the extremities of the guns. The end portions of the conductors 17 are pre-molded so that they may be inserted in these passages.

The extremities of each gun body within the couplings are provided with caps 31 of insulating material which support contact plates 32. The extremities of the conductors 17 are soldered to these plates. The central portions of the plates are raised so that when the gun bodies are joined by the couplings 2 electrical contact is established. Interposed between and filling the space between the plates, except for their contacting portions is a yieldable seal ring 33. The periphery of this ring is preferably concave so as to form pressure lips which bear against the insulated caps 31. Holes 34 are provided in each coupling so that the periphery of the seal rings 33 is subjected to submergence pressure. By this means the electrical connections between the gun bodies are isolated from contact with the well fluids. As an added precaution against electrical leakage, the interior walls of the couplings may be coated with insulating material as indicated by 35.

Operation of my gun perforator is as follows: Electrical energy to fire the gun perforator may be supplied through the cable 4 or a source carried by the gun itself and initiated by any suitable means.

The electrical energy is distributed simultaneously to the various primer cartridges 20 through the conductors 17. Each primer cartridge when ignited burns slowly at first without excessive heat or pressure. This condition obtains for a period sufficient to insure that all primer cartridges are ignited. This is of primary importance for, due to the necessary tolerance in the resistances of the various ignitor elements all primer cartridges will not ignite at once. If high pressures or explosive forces are exerted before all the ignition filaments have had oppor-

tunity to ignite their respective cartridges, the electrical connections are damaged; that is, are shorted or opened and thus in either case causing mal-functioning of the other cartridges.

In fact many prior attempts have been made, without success, to fire a large number of electrically ignited cartridges simultaneously by series or parallel connection of the ignition elements. While the reasons for such failures may be varied, it is my theory that the trouble is due to pre-ignition of certain cartridges and damage to the electrical system before the other cartridges are ignited.

After the necessary time delay the high explosive 25 is ignited in each primer cartridge. If a material such as balistite is employed, it will not detonate, at least at first, but instead will burn; but, as it burns the pressure will increase and as the pressure increases the rate of burning will accelerate until the primer cartridge will burst with explosive force into the propellant cartridge, igniting and detonating the propellant. The force with which the primer cartridge fires will of course be dependent on the rupture point of the walls of the primer cartridge and therefore the primer cartridge may be pre-designed to meet the optimum conditions under which the propellant should be fired.

It should be observed that although the primer charge may function as a detonator, neither the explosive nor the time delay means need have the sensitivity of a conventional detonating element such as those containing fulminate of mercury or lead azide. Thus, the primer charge is particularly safe.

The diameter of the primer cartridges and the bores 14 in which they fit are sufficiently small that the force against the conductor 17 and the bars 27 is held within safe limits. For example, assuming an explosive force of 200,000 pounds per square inch in the propellant chamber, the force exerted against the area of a bore 15 if this bore be one-fourth inch in diameter would be approximately 10,000 pounds. The conductor 17 and contact plug 18 when backed by the bar 27 cannot be displaced and though spoiled for further use maintain a complete seal.

Having thus described certain embodiments of my invention I do not desire to be limited thereto, but intend to claim all novelty inherent in the appended claims.

I claim:

1. A gun perforator, comprising: a gun body structure incorporating a plurality of gun units, each having a propellant cartridge; means for supplying electrical energy simultaneously to each of said gun units; and a time delay firing means interposed between said electrical supply means and each of said propellant cartridges, said means including an electrically responsive igniting element, an exothermic time delay element including a fuel and oxidizing agent ignited by momentary heating of said igniting element and adapted to continue to burn irrespective of continued operation of said ignition element, and means operable after an interval determined by said time delay element for firing the corresponding propellant charge.

2. A gun perforator comprising: a gun perforator body structure defining a plurality of gun bores, cartridge chambers therefor, and a conductor passage including branches communicating with said cartridge chambers; a conductor extending along said passage and contact means plugging said branches; a time delay means in-

terposed between each contact means and the corresponding cartridge, said time delay means including an electrically responsive ignition element, an exothermic time delay element including a fuel and oxidizing agent ignited by momentary heating of said igniting element and adapted to continue to burn irrespective of continued operation of said ignition element and means operable after an interval determined by said time delay element for firing the corresponding propellant cartridge.

3. A gun perforator, comprising: a gun perforator body structure defining a plurality of gun bores, cartridge chambers therefor, a conductor channel and branches directed inwardly from the bottom of said channel and communicating with said cartridge chambers; cartridges for said cartridge chambers; a conductor extending along said channel and including integral contact plugs extending into said branches; pressure resisting means for retaining said conductor in said channel and said contact plugs in said branches against explosive pressures generated in said cartridge chambers; and an electrically ignited time delay means in said branches for firing said cartridges.

4. A gun perforator, comprising: a gun perforator body structure defining a plurality of gun bores, cartridge chambers therefor, a conductor channel and branches directed inwardly from the bottom of said channel and communicating with said cartridge chambers; cartridges for said cartridge chambers; a conductor extending along said channel and including integral contact plugs extending into said branches; pressure resisting means for retaining said conductor in said channel and said contact plugs in said branches against explosive pressures generated in said cartridge chambers; and a time delay means in each of said branches including an electrically responsive igniting element, and an exothermic time delay element ignited thereby and adapted to continue to burn after ignition irrespective of continued operation of said ignition element, for delaying firing of the corresponding cartridge until all of said igniting elements connected with said conductor have initiated their respective time delay elements.

5. In a gun perforator wherein a plurality of gun units are fired simultaneously by a common electrical supply, the combination of a time delay means interposed between said electrical

supply and each of said gun units, each of said time delay means including an electrically responsive ignition element and an exothermic time delay element, including a fuel and oxidizing agent ignited thereby and adapted to continue to burn after ignition irrespective of continued operation of said ignition element for delaying firing of the corresponding gun unit until all of said ignition elements connected with said electrical supply have initiated their respective time delay elements.

6. A gun perforator, comprising: a cylindrical body structure defining a plurality of gun units each including a gun bore and cartridge chamber, said body structure also defining an ignition bore intersecting each cartridge chamber and a longitudinally extending conductor channel traversing said ignition bores; a conductor fitting said channel and including a contact for each ignition bore; an electrical initiated primer cartridge in each ignition bore; a retainer bar in said channel backing said conductor; and means for securing said bar therein against explosive pressures generated in said ignition bores and cartridge chambers.

7. A gun perforator, comprising: a cylindrical body structure defining a plurality of gun units each including a gun bore and a cartridge chamber, said body structure also defining an ignition bore intersecting each cartridge chamber and a longitudinally extending conductor channel traversing and communicating with said ignition bores; a conductor fitting said channel and including a contact for each ignition bore; explosive cartridges in said cartridge chambers; electrical ignition means therefor associated with said contacts; a retainer bar in said channel backing said conductor; and means for securing said bar therein against explosive pressures in said ignition bores and cartridge chambers.
